UNITED STATES PATENT OFFICE.

HARRISON D. SPANGLER, OF RUSHVILLE, INDIANA, ASSIGNOR TO NORRIS & BROTHER, OF SAME PLACE.

SEEDING-MACHINE.

SPECIFICATION forming part of Letters Patent No. 294,694, dated March 4, 1884.

Application filed November 15, 1883. (No model.)

To all whom it may concern:

Be it known that I, HARRISON D. SPANGLER, of Rushville, Rush county, Indiana, have invented certain new and useful Improvements in Seeding-Machines, of which the following is a specification.

This invention pertains to that class of seeding-machines known as "grain-drills," and relates to the mechanism used in zigzagging the drill-hoes.

The invention will be better understood from the following description, taken in connection with the accompanying drawings, in which—

15 Figure 1 is a vertical section, transverse to the axle, of a seeding-machine embodying my improvement; Fig. 2, an elevation of the racks and pinions viewed upon the face opposite to that shown in Fig. 1; Fig. 3, a plan of the racks as seen in Fig. 2; Fig. 4, a section of the draft-bars on line *b*, Fig. 6; Fig. 5, a section of side frame on line *a* of Fig. 4, and Fig. 6 a plan of the general machine.

In the drawings, A represents the usual frame of a grain-drill; B, the axle; C, the seed-box; D, the wheels; E, the tongue; F, the drill-hoes; G, the drag-bars; H, a movable longitudinal draft-bar, to which half of the drag-bars are attached in the usual manner; I, a similar draft-bar, to which the other half of the drag-bars are attached; J, housings secured to the framing and supporting the draft-bars and their operating mechanism; K, a rack secured to the upper surface of the draft-bar I; L, a pinion engaging said rack; M, a rack similar to rack K, but thinner, secured to the draft-bar H along the side of rack K; N, a pinion journaled to the housing and engaging rack M; O, a shaft reaching 25 from housing to housing and carrying the pinions L; P, a lever secured to the shaft at about its center; Q, a hand-lever provided with a detent, and arranged to oscillate the lever P, in a manner readily understood from the drawings; R, a pivoted support for the hand-lever; S, end supports and guides for the draft-bars, attached to the side framing; and T, the guiding-slot for the draft-bars in the housings.

The guiding features of the housings and of 30 the end supports, S, are arranged at an angle,

as shown, whereby the movement of the draft-bars occurs in a plane disposed toward parallelism with the drag-bars. Each of the draft-bars is provided with a rack at each of the housings, and at each of the housings pinions 55 are provided for operating the racks. The pinions receive motion indirectly from the hand-lever through the instrumentality of the shaft O, which rotates the pinions uniformly, and gives to the draft-bars parallel movements 60 as they separate and approach each other in zigzagging the hoes, as usual, and for the usual purpose. The pinions L, which turn with the shaft O, gear with the rack K, and therefore give motion to the draft-bar I. The pinions 65 L have very much broader faces than their racks. The pinions N gear into the pinions L and into the racks M, and are therefore rotated by the pinions L and give motion to the draft-bar H. The pinions L are set so high 70 that they will not engage the racks M, and the racks K are of sufficient height to be engaged by these high-set pinions. Each rack is provided with a projection resting upon the bar to which it is not attached, which aids in 75 steadyng the parts.

By the means described a uniform shifting motion in a true plane is given to the draft-bars upon operating a hand-lever located at about mid-length of the draft-bars.

80

I claim as my invention—

1. In a grain-drill, the combination, substantially as set forth, of the machine-framing, a pair of shifting draft-bars, hoes and drag-bars attached to the draft-bars, in the manner 85 specified, means for shifting the draft-bars, and angularly-arranged guides for the draft-bars, as specified.

2. In a grain-drill, the combination, substantially as set forth, of the machine-framing, a pair of shifting draft-bars having drag-bars 90 and hoes attached, a hand-lever, guides for the draft-bars, a pair of racks, as set forth, secured to each draft-bar, pinions engaging each other in pairs and engaging the racks, 95 and a shaft uniting the pairs of pinions.

HARRISON D. SPANGLER.
